TUB AND SUPPORT THEREFOR

William W. Galbreath, Alliance, Ohio, assignor to
 The Steel Sanitary Company, Alliance, Ohio, a
 corporation of Ohio

Application February 1, 1940, Serial No. 316,772

4 Claims. (Cl. 4—173)

This invention relates to a bath-tub and support therefor and, in particular, to a bath-tub composed of sheet steel stampings.

Bath-tubs composed of sheet steel stampings have numerous advantages such as light weight, low cost, etc. While the light weight of such tubs is a distinct advantage in most respects, it gives rise to a slight difficulty in installation, viz., the danger of shifting about while connections thereto are being made, thereby rendering the installer's work more difficult.

I have invented a novel tub and support therefor whereby the foregoing objection to sheet metal tubs as now made is entirely overcome. In a preferred embodiment of the invention, I install a horizontal supporting member of any suitable type, such as a horizontal stringer secured to the studs of the wall adjacent which the tub is to be positioned. I also provide lugs depending from the edge of the tub adapted to be disposed adjacent the wall, said lugs projecting downwardly and adapted to hook over the stringer, thus firmly anchoring the tub in proper position.

The aforementioned embodiment of the invention is illustrated in the accompanying drawing, in which

Fig. 1 is a partial elevation of an incomplete partition wall with a tub thereadjacent embodying the invention;

Fig. 2 is a transverse sectional view taken along the plane of line II—II of Fig. 1;

Fig. 3 is a partial perspective view illustrating a detail; and

Fig. 4 is a view similar to Fig. 3 showing a modification.

Referring now in detail to the drawing, a tub 10 has a well or body portion 11 and a rim 12 extending around the periphery thereof. A side apron 13 extends downwardly from the rim 12 on one side of the tub. If the tub is designed for installation in a corner, the tub may also have an end apron 14. A flange 15 is bent up from the rim 12 along the other side and end of the tub. Braces 16 and 17 extend downwardly from the end and side of the tub to the side and end aprons 13 and 14.

The tub and aprons are formed from sheet metal stampings which are welded or otherwise secured together. When installed, the tub is supported by the aprons 13 and 14 which bear on a floor 18, and by the portion of the rim 12 adjacent the wall. The drawing illustrates an incomplete wall including spaced studs 19 resting on a plate 20. Joists 21 bearing on the plate support the floor 18. Short posts 22 extend upwardly

from the joists along the studs 19 and support a horizontal stringer 23 which may conveniently be nailed to the studs 19. As shown in Figs. 1 and 2, the stringer 23 provides a support at the proper height to engage the portion of the rim 12 adjacent the wall to support the tub in cooperation with the aprons 13 and 14 bearing on the floor 18. The flange 15 prevents water from getting in under the plaster forming the finished wall and dripping down behind the tub. In finishing the wall, the plaster is brought down inside the flange 15.

Lugs or tongues 24 are spaced along the side flange 15 and are secured thereto in any convenient manner, as by welding. As shown in the drawing, the dimension of the lugs measured along the length of the tub is small relative to the spacing between studs. The lower ends of the lugs extend downwardly below the rim 12 and are preferably offset slightly from the vertical plane of the flange 15, as shown in Fig. 2. By virtue of this construction, the lugs 24 engage behind the stringer 23 and prevent shifting of the tub away from the wall by forces that may be applied thereto while making pipe connections to the tub. After installation has been completed, the tongues 24 continue to provide an anchorage effective to hold the tub to the wall. Since the tongues are behind the flange 15, they are entirely concealed when the wall is completed.

The tongues 24, instead of being separately formed and welded to the flange 15, as shown in Figs. 1 through 3, may be formed by notching the flange as shown at 25 in Fig. 4, and bending down portions of the flange to form tongues such as that shown at 26. The tongues 26, of course, serve in precisely the same manner as the tongues 24 to anchor the tub to the wall.

It will be apparent from the foregoing description that the invention provides a simple, inexpensive, yet effective, means for anchoring a tub in proper position to prevent shifting while pipe connections are being attached thereto, which has heretofore caused considerable difficulty for the plumber, because of the relatively light weight of tubs composed of sheet steel stampings.

Although I have illustrated and described but a preferred embodiment of the invention and a modification, it will be understood that it may be embodied in forms other than those shown, without departing from the spirit of the invention or the scope of the appended claims.

I claim:

1. A tub having a rim extending outwardly therefrom along one side thereof, the under surface of said rim being substantially plane and adapted to rest on the top of a substantially horizontal supporting means secured to spaced wall studs, and securing lugs rigidly connected with and depending below the level of said rim, said lugs being spaced apart and of a small dimension along the length of the tub relative to the spacing between studs, whereby the rim may be set on the supporting means with the lugs extending between the studs and hooking over the top of the supporting means to prevent lateral displacement of the tub.

2. A tub as defined in claim 1 characterized by said rim having an upturned flange at its edge, said lugs being composed of portions of said flange extending outwardly and downwardly from the remainder thereof.

3. A tub as defined in claim 1 characterized by at least the portions of said lugs below the level of said rim being offset outwardly from the edge of said rim.

5 4. A tub having a rib extending outwardly therefrom along one side thereof, the under surface of said rim being substantially plane and adapted to rest on a substantially horizontal stringer having a plane upper surface and secured to spaced wall studs, and securing lugs rigidly connected with and depending below the level of said rim, said lugs being spaced apart and shorter along the length of the tub than the spacing between studs, whereby the rim may be set on the stringer with the lugs extending between the studs and hooking over the inner side of the stringer to prevent lateral displacement of the tub.

WILLIAM W. GALBREATH.
